CANDLE HOLDER FOR CAKES AND THE LIKE

Raymond B. Blumenshine, Dormont, Pa.

Application April 22, 1959, Serial No. 55,610

Term of patent 14 years

(Cl. D48—2)

Fig. 1

I claim:

The ornamental design for a candle holder for cakes and the like, as shown and described.
